DESIGN FOR BACK OF BRUSHES.

No. 38,090:

Specification for Design.

Patented June 19, 1906.

Application filed May 16, 1906. Serial No. 317,250. Term of patent 14 years.

To all whom it may concern:

Be it known that I, WILLIAM C. CODMAN, a subject of the King of Great Britain, residing at Providence, in the county of Providence and State of Rhode Island, have invented a new, original, and ornamental Design for the Back of a Brush, reference being had to the accompanying drawing.

The figure in the drawing is the back view of a brush, showing my design.

I claim—

The ornamental design for the back of a brush, as shown.

WILLIAM C. CODMAN.
